UNITED STATES PATENT OFFICE

HARRY C. HARDING, OF WILKES-BARRE, PENNSYLVANIA

DESIGN FOR A TYPEWRITER PAD

Application filed July 28, 1931. Serial No. 40,705. Term of patent 14 years.

To all whom it may concern:

Be it known that I, HARRY C. HARDING, a citizen of the United States, residing in Wilkes-Barre, in the county of Luzerne, and State of Pennsylvania, have invented a new, original, and ornamental Design for a Type-
writer Pad, of which the following is a specification, reference being had to the ac-

companying drawing, forming part thereof.

The figure is a perspective view of a type-
writer pad showing my new design.

I claim:

The ornamental design for a typewriter pad as shown.

HARRY C. HARDING.
